Attorney.

UNITED STATES PATENT OFFICE

RUDOLF KRONENBERG, OF HAUS KRONENBERG, POST IMMIGRATH, GERMANY

CONSTRUCTIONAL FORM OF ROLLING MILL

Original application filed August 28, 1929, Serial No. 389,077, and in Germany April 17, 1929. Divided and this application filed September 24, 1930. Serial No. 484,185.

The present application is a division of my co-pending application filed August 28th, 1929, Serial No. 389,007, applications filed in Germany on April 17, and June 20, 1929.

5 This invention relates to an improved constructional form of the rolling mill shown and described in, and forming the subject-matter of, my United States Patent No. 1,697,012, the main features of which relate, according to 10 its claim 1, to a multiplicity of rollers, one of which is mounted for oscillatory movement with respect to the other, and of cooperating means, one of which is movable in the arc of a circle with respect to the other to prevent 15 uneven rolling of the material between said rollers. In other words one of the rollers is so arranged and supported that it can oscillate around a continuously stationary centre of oscillation in the plane passing through the roller axes; this arrangement and manner of operation has been rendered possible by 20 providing the supporting body for the two bearings of the oscillable roller with a circularly curved surface extending around the centre of oscillation of said roller, said surface contacting with a correspondingly shaped hollow cylinder supported by the adjustable roller adjusting spindles.

There are shown and described, also 25 claimed, in said United States patent several devices for effecting the adjustment of the supporting body which co-operates with the circularly curved surface mentioned.

Now the present invention relates to a particularly practical constructional form of a device for adjusting the circularly curved supporting body for the bearing places of the roller, this constructional form being so designed that any end play or lost motion 30 when the supporting body is adjusted or readjusted or reversed is completely obviated. This constitutes a considerable progress, in that with the known devices and their various constructional forms the end play or lost motion from which they suffered have proved detrimental. I attain the new object in view by providing means engaging the supporting body laterally from both sides of the engaging part of the same and being an inter-action with one another, said means be-

ing subjected to a certain preliminary or pressing tension.

The invention is illustrated in the accompanying drawings.

Fig. 1 is a section.

Fig. 2 is a side view.

Fig. 3 is a section through the upper half of Fig. 1.

Fig. 4 shows a modification concerning the shifting of the centre of oscillation.

Fig. 5 is a side view of the modification.

The subject matter herein claimed constitutes a division of my Patent No. 1,811,586, issued June 23, 1931.

Concerning the constructions shown in Figs. 1, 2 and 3 the bodies or members *i* and *k* are practically such as in Fig. 1 of the Patent No. 1,811,586, dated June 23, 1931, the member *k* being also in this case concave on its bottom face and the member *i* being convex on its top face. The two members are located between guide members 70 and 71, of which 71 can follow the oscillatory movement of the member *i*, but which both (70 and 71) cannot (counter to the arrangement in Figures 1 and 2) be shifted in the axial direction of the rollers *d* and *a*. The cross-sectional shape of the said guide members 70 and 71 appears distinctly from Figure 5. The guide member 70 resembles in transverse 80 section an inverted U and embraces or encloses the concave body member *k*, whereas the guide member 71, more precisely, its upper portion, resembles in transverse section a U and embraces or encloses the convex body member *i*. At each frontal side of the guide member 70 are horizontal bridges 72, of which each supports a pressure spindle 73, and 74 respectively, by which both members *i* and *k* can be shifted in and between said guide members 70 and 71, both members *i* and *k* being shifted at a time. The members *i* and 85 71 are connected with one another by screws 75 or the like threaded into the members.

If the bodies *i* and *k* are to be shifted so as to shift at the same time their centers of oscillation, the screws 75 are unscrewed so as to disconnect the body *i* from the guide member 71, and now both bodies *i* and *k* together can be shifted by means of the screws 90

73 and 74. The threaded pores provided in the body *i* for the reception of the screws 75 are at those faces where they terminate so extended horizontally in opposite directions 5 as to form slots 76 (Fig. 1) in which the ends of said bolts can be shifted and which determine the maximum length of the shifting of the said body *i*. The slots 76 are formed in the part 71. This maximum length is indicated in Fig. 1 by the dotted line 77. Within the length of this line any desired point can be chosen as centre of oscillation, so that also if narrow rolling material is to be dealt with the operative circumferential surface of the 15 rollers can be fully utilized. The part *i* is oscillated as shown in my prior patent above referred to.

In the second constructional form shown in Figs. 4 and 5, the members *i* and *k* are 20 practically the same as in Fig. 1. The concave member *k* is stationary and the convex member *i* can be turned in it so as to vary the pressure which the rollers exert upon the material to be rolled. The mechanism for 25 thus turning said body *i* may be of any desired design, for instance such as has already been described with respect to the other figures.

When the body *i* is moved relatively to the body *k* the oscillatory axis 80 maintains 30 always its position, viz., in the middle plane of the mill. But the two rollers *a* and *d*, together with their braces *f* and *h*, as well *f*¹ and *h*¹, and the supporting bodies 71 and 81, can be shifted laterally and parallel to the 35 axis of the rollers, whereas the bodies *i* and *k* do not take part in the shifting. If the rollers together with the supporting parts are moved in one or the other of the possible two directions another point in the oscillatory axis 80 forms the centre of oscillation. The 40 operating circumferential surfaces of the rollers can, thus be used and utilized at any desired portion where the material to be rolled may be passed through.

45 The extreme positions of the parts *f*, *h*, 71 and 81 are indicated by dotted lines in Fig. 4.

While in the present instance the part *i* is 50 oscillated in the same manner as in my prior patent, above referred to, in the present instance, there is a material difference in the operation and the arrangement of parts. The means for moving the parts *i'* and *k'* in the prior patent are by no means the equivalent of the screws 73 and 74 of the present application. In the present instance the screws 55 73 and 74 are not for the purpose of and do not serve to move the parts *i* and *k* towards one another, but these screws operate to shift the parts *i* and *k* jointly, that is, both are moved together over the leaders 70 and 71, on that they are shiftably adjusted over the leaders 70 and 71, and the part 71 can follow the shifting movement of the part *i*. Yet, 60 both the parts 70 and 71 cannot be shifted in the direction toward the axle roller. This 65

forms not only a different arrangement, but a different action, or operation, for a different and useful purpose, not capable of being attained by my prior patent.

In practice I have found it desirable to 70 regulate at will the shifting point of the regulating part 77, so that thereby a uniform wearing off of the rollers is obtained when narrow rollings are made.

What I claim is:

1. A rolling mill, comprising, in combination with the rollers and their trunnion bearings, a member bearing upon the braces of the upper roller and having upwardly directed parallel ledges on its top; a body having a convex top face, another member having a concave bottom face and receiving said convex member in it; and means for shifting these members simultaneously in axial direction 80 jointly, substantially as set forth.

2. A rolling mill, comprising, in combination with the rollers and their trunnion bearings, a member bearing upon the braces of the upper roller and having upwardly directed parallel ledges on its top; a body having a convex top face and receiving said convex member in it; a member overlapping and enclosing the part having the concave surface and another member located below and enclosing, the part having the convex surface; 90 said latter two members being stationary and the said concave and the said convex part being shiftable jointly between them, and means for affecting this shifting of said members jointly, substantially as set forth.

3. The rolling mill, comprising, in combination with the rollers and their trunnion bearings, a member bearing upon the braces of the upper roller and having upwardly directed parallel ledges on its top; a body having a convex top face, and another member having a concave bottom face and receiving said convex member in it; a member overlapping and enclosing the part having the concave surface and another member located below, and enclosing, the part having the convex surface; 100 said latter two members being stationary and said concave and the said convex part being shiftable between them; adjustable screws bearing on the frontal faces of the concave part and adapted to move said parts jointly, and means holding said screws in connection with the part located above, and enclosing, the said concave part, substantially as set forth.

4. A rolling mill, comprising, in combination with the rollers and their trunnion bearings, a member bearing upon the braces of the upper roller and having upwardly directed parallel ledges on its top; a body having a convex top face, and another member having a concave bottom face and receiving said convex member in it; a member overlapping and enclosing the part having the concave surface and another member located 115

below, and enclosing, the part having the convex surface; said latter two members being stationary and the said concave and the said convex part being shiftable between them; screws extending through the lower member 5 which supports and encloses the convex part into slots in this part, said screws serving to move said parts jointly substantially and for the purpose set forth.

5. A rolling mill, comprising, in combination with the roller and their trunnion bearings, a member bearing upon braces of the upper roller and having upwardly directed parallel ledges on its top; a body having a convex top face, another member having a 15 concave bottom face and receiving said convex member in it; and means for shifting these members simultaneously in axial direction with milling rollers having each a separate operating middle portion of larger diameter than the other portions, trunnion bearings contacting with these latter portions; shiftable members below and above said bearings, and means for shifting them together with said rollers jointly in one direction, substantially and for the purpose set forth.

In testimony whereof I affix my signature.
RUDOLF KRONENBERG.
